UNITED STATES PATENT OFFICE.

ABRAHAM J. ZIV, OF CHICAGO, ILLINOIS.

DESIGN FOR A STATUETTE.

55,543.

Specification for Design. Patented June 22, 1920.

Application filed August 8, 1919. Serial No. 316,273. Term of patent 3½ years.

To all whom it may concern:

Be it known that I, ABRAHAM J. ZIV, a citizen of the United States, residing in Chicago, Cook county, Illinois, have invented a certain new, original, and ornamental Design for a Statuette, of which the following is a specification.

In the accompanying drawings, which form a part of this specification and illustrate my novel statuette, Figure 1 is a view mainly from the front but a little to one side, and Fig. 2 is a side view of the statuette.

I claim:

The ornamental design for a statuette substantially as shown.

ABRAHAM J. ZIV.
